UNITED STATES PATENT OFFICE.

GOTTHOLD L. LANGER, OF STOCKTON, CALIFORNIA, ASSIGNOR TO JOSEPH GEIGER, OF STOCKTON, CALIFORNIA.

TWO-CYCLE MOTOR.

No. 893,738.

Specification of Letters Patent.

Patented July 21, 1908.

Application filed September 19, 1906. Serial No. 335,263.

To all whom it may concern:

Be it known that I, GOTTHOLD L. LANGER, a citizen of the United States, and a resident of Stockton, county of San Joaquin, and 5 State of California, have invented certain new and useful Improvements in Two-Cycle Motors; and I do declare the following to be a full, clear, and exact description of the same, such as will enable others skilled in the 10 art to which it appertains to make and use the same, reference being had to the accompanying drawings and the characters of reference which form a part of this specification.

15 This invention relates to improvements in gas motors and particularly to the type known as two cycle.

The main objects of my invention are as follows: First: to produce a compact, light 20 and simple motor. Second: to produce a motor of the type set forth in which there will be no premature or irregular explosions. Third: to produce a two cycle motor in which any number of cylinders may be used as de- 25 sired. Fourth: to produce a motor in which all the power generated will be concentrated at the proper point. Fifth: to produce a motor which in all its parts is designed to do rapid, effective work and still remain cool. Sixth: to produce a motor which although 30 thoroughly effective in all its works will be comparatively simple of construction and easy to repair. All these objects and many minor ones not mentioned are obtained by 35 means of vertical cylinders arranged in series, each cylinder being provided with separate compression and explosion chambers, the compression chamber of one being connected with the explosion chamber of another by suitable ports and passages, and by such other and further construction as will appear by a perusal of this specification and the claims appended.

In the drawings similar characters of refer- 45 ence indicate corresponding parts in the sev- eral views.

Figure 1 is a sectional side elevation, Fig. 2 is a section on the line $y-y$ of Fig. 1, Fig. 3 is a section on the line $x-x$ of Fig. 1.

50 I first provide a hollow base composed of portions 1 and 2, a crank shaft 3' having spaced cranks 3 and 3" extending in opposite directions and being suitably journaled in

journal boxes 4 held in said base by means of cross members 5. Suitably secured to the 55 portion 2 of the two-part base are two or more vertical cylinders 6, said cylinders having upper chambers 7 enlarging into lower chambers 8, said upper chambers being formed with hollow reentrant heads 9 extending downward 60 therein, and said upper chamber also having a depending ring or flange 8a. Arranged in the chambers 7 are pistons 10 provided with upwardly projecting guide members 11, ex- 65 tending between said heads and the bodies of the cylinders, and with enlarged portions 12 bearing against the sides of the chambers 8. 13 are driving rods connecting said pistons to the cranks of the shaft 3'.

14 are intake check valves connected with 70 the chambers 8 by means of passages 15 leading from the said chambers 8 to the alternate chambers 7, and 16 are air intake pipes having check valves 16', the pipes being connected with said passages 15 above said in- 75 take check valves 14.

In the guide members 11 are ports 17 adapted to open the passages 15 into the alternate chambers 7 when the pistons are in their lowest position, and 18 are similar ports 80 adapted to open exhaust ports 19, located near the lower end of the chamber 7 and be- 85 tween the air intake port and oil intake port, when the pistons reach their lowest position.

20 is a water jacket extending all around 85 the chamber 7.

21 are the usual spark plugs extending into the top of the chambers 7.

22 and 23 are packing rings arranged at the lower end of the sides of the heads 9. 90

24 are packing rings arranged near the head of the pistons 10 for the purpose of in- creasing the packing area of the piston.

In using the device the downward drive of the pistons draws into the chambers 8 a suffi- 95 cient quantity of oil through the valves 14 and a quantity of external air through the valves 16', said external air passing through the passages 15. The upward drive of the pistons then compresses this air and oil near 100 the upper end of said chambers 8; and when the ports 17 open the passages 15 into the alternate chambers 7 the pressure causes the comparatively pure air from the passages 15, as described, to first pass into the alternate 105 chambers 7, thus clearing all the dead gases

therefrom and preventing a premature explosion when the compressed mixture of air and oil from the chambers 8 enters. By the arrangement of the air ports 16 above the oil ports 14 the air enters the chamber 7 first consequently a quantity of pure air is always in the passages 15 ahead of the air and oil from the chambers 8. When the mixture of air and oil does enter said chambers 7 the sparks from 21 cause an explosion which drives the pistons backward and then the ports 18 open the ports 19 to the exhaust. The same operation described takes place alternately in the chambers 7 since the passages 15 lead from one of the chambers 8 to the alternate chamber 7. Water running through the jacket 20 keeps the chambers 7 cool.

As will be seen the main features by means of which the desired ends are attained are the enlarged chambers 8, and the enlarged pistons working therein forming efficient means for compressing the mixture; also the feature of forcing the mixture alternately from the said mixing chambers to the alternate explosion chambers, thus always giving the said explosion chambers a sufficient chance to exhaust the dead gases before the new charge enters; also the feature of the heads 9 and the guide members 11 provided with the ports 17 and 18 whereby the engine is equipped to permit the exhaust of the exploded gases and the entrance of the new charge.

35 While I have set forth in some detail the main features of the present and preferred embodiment of my improved motor, still I do not desire to be restricted to such specific detail, as many small changes in the construction thereof may be resorted to at will without departing from the spirit of my invention.

Having thus described my invention what I claim as new and desire to secure by Letters Patent is:

1. In a motor, a hollow base, a pair of spaced cylinders mounted upon said base and connected at one end therewith, the upper portion of each cylinder being smaller in diameter than the lower portion, said upper portion of each cylinder constituting an explosion chamber, the said lower portion adapted to serve as a pump, passages in the walls of said upper portions, ports through the walls of the cylinders at the ends of said passages whereby communication is established between the enlarged portion of one cylinder and the smaller portion of the other cylinder, the port at the upper end of each passage constituting an inlet for the explosion chamber, an oil intake port and an air intake port for each cylinder, said ports being spaced apart and leading into the aforesaid passages, an exhaust port in the wall of each cylinder, closures at the outer ends of said cylinders

and provided with hollow reentrant heads depending within the cylinders and spaced from their inner surfaces, transverse ports in said heads opposite the air intake ports of the cylinders, pistons operating within said cylinders and provided with guide members operating between said reentrant heads and said cylinders, and spaced ports in said guide members adapted to be aligned with the explosion chamber inlet ports and the exhaust ports respectively, and enlarged portions carried by said pistons operating in the enlarged portions of the cylinders.

2. In a motor, a hollow base, a crank shaft journaled in said base, cylinders mounted upon said base and connected at one end therewith, said cylinders each having two portions of different diameters, the enlarged portion of each cylinder being adapted to serve as a pump and the smaller portion of each cylinder as an explosion chamber, passages in the walls of the smaller diameter portions of said cylinders, ports at the upper ends of said passages communicating with the explosion chambers and constituting inlet ports therefor, and ports at the lower ends of said passages communicating with the pumps, an oil intake port and an air intake port spaced apart and leading into each passage, exhaust ports in the walls of the cylinders, closures at the outer ends of said cylinders and provided with hollow reentrant heads depending within the explosion chambers and spaced from the sides thereof, pistons operating in said cylinders and provided with extending guide members operating between the walls of the explosion chambers and the depending reentrant heads and having spaced ports adapted to register with the inlet ports of the explosion chambers and the exhaust ports respectively, enlarged portions carried by said pistons operating in the enlarged portions of the cylinders, connecting rods between said pistons and crank shaft, and a sparking igniter connected through each of said hollow heads.

3. In a motor, a hollow base, a shaft having oppositely disposed cranks and journaled through said base, two cylinders each having two portions of different diameters, the enlarged portion of each cylinder being adapted to serve as a pump, and the smaller portion as an explosion chamber, said cylinders being mounted upon the hollow base and connecting at one end therewith and provided with passages in the walls thereof affording communication between the enlarged portion of each cylinder and the smaller portion of the other cylinder and with ports at the juncture of the larger and smaller portions of said cylinders connecting the enlarged portions of said cylinders with said passages, and ports intermediate the ends of the smaller portions of the cylinders.

ders connected with said passages, an oil intake and an air intake leading respectively to each passage, depending closure heads at the outer end of the cylinders, pistons operating respectively in both portions of said cylinders and provided with extending guide members operating between the depending closure heads and the cylinders, and con-

necting means between the pistons and the crank shaft.

In testimony whereof I affix my signature ¹⁰ in presence of two witnesses.
